United States Patent Office.

PATRICK LENNOX, OF LYNN, MASSACHUSETTS.

Letters Patent No. 80,829, dated August 11, 1868.

IMPROVED MACHINE FOR BEAMING HIDES.

The Schedule referred to in these Letters Patent and making part of the same.

TO ALL TO WHOM THESE PRESENTS SHALL COME:

Be it known that I, PATRICK LENNOX, of Lynn, in the county of Essex, and State of Massachusetts, have invented certain new and useful Improvements in Machines for Beaming Hides; and do hereby declare the following to be a full, clear, and exact description thereof, due reference being had to the accompanying drawings, making part of this specification, and in which—

Figure 1 is a side elevation, and

Figure 2 a vertical central and longitudinal section of my invention.

Figure 3 is an inner end elevation, and

Figure 4 an under side view of the movable car, to be hereinafter referred to.

This invention, in some respects, may be considered as an improvement upon that for which Letters Patent of the United States were granted to myself and Thomas Roberts, on the 29th day of October, 1867, although the present machine possesses features and characteristics which in themselves are not necessarily to be considered in connection with such Letters Patent.

The first point of my present invention consists in a novel mode of effecting the reciprocating rectilinear movements of the beaming-tool carrier, and of raising it above the surface of the operating-bed or tablet of the machine at the proper time.

Second, in a mode of supporting and effecting the vertical movements of the operating-tablet.

Third, in an elastic cushion or bed-piece, applied to the top of the operating-tablet, in manner and for the purpose as hereinafter explained.

Referring to the accompanying drawings, it will be seen that A denotes a frame, properly constructed, for receiving and supporting a horizontal shaft, a, upon the inner end of which a balance-wheel, b, is fixed, this wheel having a crank-wrist pin, c, applied to its outer face.

The frame A has a long arm, d, extending horizontally from it and toward the remaining operative parts of the machine, a sliding block or carriage, e, sliding upon this arm, and having jointed to its lower end the beaming-tool holder f, the sliding carriage e being connected to the wrist-pin c by a connecting-rod, g, and so that revolutions of the balance-wheel b shall cause a reciprocating rectilinear movement of the sliding carriage e and tool-holder f, the latter being pivoted to one end of an eccentric-rod, h, the eccentric-strap, z, of such rod encompassing an eccentric-block, j, fixed to the balance-wheel and about the wrist-pin c, the arrangement of the eccentric-block j with respect to the wrist-pin being such that upon a forward movement of the sliding carriage and tool-holder, the beaming-tool k shall be raised above and from off the hide or its supporting-tablet, while upon a reverse or inward movement of such carriage and tool-holder, the beaming-tool shall be maintained in a rigid and nearly upright position, and brought forcibly in contact with the hide or its tablet.

In order to insure the rising of the beaming-tool from above the hide as it approaches its extreme outward movement, the outer extremity of the horizontal arm d is inclined upward at a small angle, as shown at a' in the drawings.

The movable car for supporting the hide or side of leather is shown at k as composed of a rectangular or other proper-shaped tablet, e', carrying upon its under side, and partially supported by, a swivelling-post, b, which is upheld by a suitable truck, M, and so as to revolve freely therein.

This truck M is composed of a rectangular frame, m, carrying four or any other suitable number of wheels, c c c e, &c., and being further provided with a circular platform, n, surmounting it, and sustained in position by spiral springs o o o o, suitably applied and confined, the object of these springs being to form an elastic or yielding foundation for the tablet e'.

For the purpose of reducing friction upon the tablet e', I apply to its under side, and so as to rest and roll upon the top surface of the platform n, four or any suitable number of casters or rollers p p, &c.

Two parallel rails, q q, are applied to the flooring of the machine, and in alignment with the movements of the beaming-tool, and serve to support and guide the movements of the movable car k.

As the construction of this movable car is the same, in this instance, with one exception, as that shown in Letters Patent before referred to, and as the general operation of the whole machine is fully explained therein, I omit an extended description of its operation.

My improvement upon the movable car consists in combining the platform *n* with the truck-frame in such manner as to be enabled to elevate or depress the forward or inner end of such platform and the supporting-tablet, in order to the more readily introduce the hide to the action of the beaming-tool.

In carrying out this portion of my present invention, I support the inner end of the platform *n* upon a cross-frame, *o'*, which extends across the truck-frame, and between its side rails, as shown in the drawings, and I support this cross-frame in turn upon the inner and shorter arm of a lever or treadle, *p*, extending along underneath the truck-frame, and centrally thereof, and pivoted to a bracket, *q*, depending from the under side of the truck-frame, the outer and longer arm, *r*, of the lever *p*, extending in advance of the truck-frame, and into a position to enable the workman to easily place his foot upon it.

After the hide has been secured to the tablet, and the car run forward under the beaming-tool, the workman is to place his foot upon the treadle and depress it. This will elevate the cross-frame *o'*, and by so doing will also elevate the inner end of the tablet *e'*, and bring it and the hide up to and in contact with the beaming-tool.

Were it not for this vertical adjustment of the tablet, much inconvenience would ensue in running the movable car back and forth beneath the beaming-tool, this inconvenience, in fact, having manifested itself in the practical use of the machine described in Letters Patent before referred to.

The third portion of my invention, in the order hereinbefore enumerated, consists in the application of an elastic apron or cushion, *s*, applied to the upper surface of the operating part of the revolving tablet *e'*, as shown in the drawings, the apron, in this instance, being composed of vulcanized India rubber. The object of this India-rubber apron is to prevent the slipping about of the hide upon the tablet, and to cause it to adhere thereto under the action of the beaming-tool.

I would remark that in place of the wheels and axles, as a means of moving the car *k*, I have contemplated the employment of sliding ways or guides applied to the car to slide upon the rails *g g*.

I claim as my invention, and desire to secure by Letters Patent of the United States, as follows:

1. I claim, in a machine for beaming hides, or sleeking or dressing leather, actuating the movements of the working-tool by means of the connecting-rod *g* and eccentric-rod *h*, the former being pivoted at one end to the sliding carriage, and the latter to the beaming-tool carrier, and both being connected with the balance-wheel by the means above described, the whole being arranged and operating as before described.
2. I claim the application of the elastic apron to the revolving tablet, in manner and for the purposes as hereinbefore explained.
3. I claim applying the revolving tablet to the car-truck frame, in such manner as to be enabled to adjust its vertical positions, essentially as herein shown and described.
4. I claim the means for accomplishing this vertical adjustment of the revolving tablet, the same consisting of the cross-frame *o* and treadle *p*, combined and arranged and operating as before explained.
5. I claim the inclination of the outer end of the horizontal beam or guide for elevating the beaming-tool, substantially as before explained.

P. LENNOX.
